UNITED STATES PATENT OFFICE.

CHARLES CAMPBELL, OF PHILADELPHIA, PENNSYLVANIA.

DESIGN FOR A PEDESTAL FOR FURNITURE OR SIMILAR ARTICLES.

53,564.

Specification for Design.

Patented July 15, 1919.

Application filed February 28, 1919. Serial No. 279,892. Term of patent 14 years.

To all whom it may concern:

Be it known that I, CHARLES CAMPBELL, a subject of the King of Great Britain, residing at Philadelphia, county of Philadelphia, and State of Pennsylvania, have invented a new and original and ornamental Design for a Pedestal for Furniture or Similar Articles, of which the following is a specification, reference being had to the accompanying drawing, forming a part thereof.

The figure is a side elevation of the stand illustrating my design.

I claim:

The ornamental design for a pedestal for furniture or similar articles, as shown.

CHARLES CAMPBELL.
